Primary Examiner — Melanie H Tung(74) *Attorney, Agent, or Firm* — Sterne, Kessler, Goldstein & Fox P.L.L.C.(57) **CLAIM**

The ornamental design for an icon for a portion of a display screen, as shown and described.

DESCRIPTION

The FIGURE is a front view of an icon for a portion of a display screen showing my new design.

The broken line showing of a portion of the display screen is for the purpose of illustrating environmental structure and forms no part of the claimed design.
